HEAT EXCHANGER

George T. Jacocks, New Rochelle, N. Y., assignor
to The Lummus Company, New York, N. Y., a
corporation of Delaware

Original application November 13, 1937, Serial
No. 174,330. Divided and this application May
18, 1940, Serial No. 335,921

6 Claims. (Cl. 257—225)

This invention relates to improvements in heat exchangers, more particularly of the fluid type in which one fluid is normally conducted through the interior of a series of tubes and another fluid, in heat exchange relation, is maintained in contact with the exterior of the tubes.

One of the principal objects of my invention is to provide a heat exchanger, the tube bundle of which has a bundle wrapper, so that more intimate contact and more effective control can be had between the external fluids and internal fluids in heat exchange relation, the tube bundle being removable from the shell for inspection and cleaning.

Another object of my invention is to provide internal retractable connections for the nozzle of a heat exchanger so that the connections may be broken between the nozzle and channel or nozzle and bundle wrapper without breaking any external pipe connections.

Further objects and advantages of my invention will appear from the following description of preferred forms of embodiment thereof, taken in connection with the attached drawings illustrative thereof, and in which:

Fig. 1 is an elevation of a heat exchanger with parts broken away and shown in section;

Fig. 2 is an enlarged vertical section of the retractable nozzle for the channel end of the heat exchanger;

Figs. 3 and 4 are similar vertical sections showing the modified forms of channel construction.

In accordance with one form of embodiment of my invention, the heat exchanger generally shown in Fig. 1 consists primarily of a shell 10 of substantially constant diameter or cross section from end to end, which is reinforced at the channel end by skirt 11, such shell being sealed at the open end by the cover 12 and at the other end by the fixed tube sheet 14. The tube sheet 14 supports the tube bundle generally indicated at 15, such tube bundle including a plurality of tubes suitably expanded within the fixed tube sheet 14 and extending to the floating tube sheet 16, as is well-known. The floating tube sheet 16 is provided with a channel spacing member 17 and a floating tube sheet cover 18 which, being spaced from the floating tube sheet 16, provides a channel for the continuous flow between the respective tubes.

The fixed tube sheet end of the heat exchanger is provided with a channel 21 communicating with the inlet and outlet nozzles 22 which are mounted on the shell. The channel is completed

by a channel cover 23 and this is preferably detachable for inspection purposes. The intermediate pass baffle 24, which distributes the circulating fluids into and out of the tubes, may be integral with or detachable from the channel 21. It will be apparent with the arrangement as shown that the heat exchanger is of two-pass type on the tube side, although any other arrangement could be made by varying the position and numbers of channel baffle 24 and the form of the channel spacing member 17.

A multiple number of passes on the shell side with a continuous floating tube sheet 16 is also possible by using a bundle wrapper 27 which is adapted to closely embrace the tube bundle 15, such bundle wrapper engaging shoulders on the fixed tube sheet 14 and the floating tube sheet 16. The bundle wrapper is preferably a continuous sheet of metal having a lap joint 28. The multiple pass is established by a plurality of longitudinally extending baffles 30 of relatively thin metal placed between the tube rows. In addition, a plurality of lateral baffles 32 are provided and these may be of half-moon or other desired configuration. Without going into the details of the baffle arrangements possible, it will be apparent that with a bundle wrapper many forms are possible and any arrangement can be had for the desired fluid course between the shell nozzles 33.

A preferred manner of holding the wrapper in the lapped position heretofore described is by a series of straps 46, each having a metal sleeve 47 overlapping the strap ends. When the ends of the straps are drawn tight as by a suitable tool, not shown, the sleeve 47 and the ends of the straps 46 are crimped or otherwise deformed for a positive and permanent tension-resisting seal. The seal is permanent and, as the straps are relatively thin, no interference occurs with the shell when the bundle is withdrawn. A plurality of straps are generally used and one is conveniently provided at the attachment to the tube sheets as well as at the respective lateral baffles 32 so that seepage between the lateral baffles and the bundle wrapper 27 is substantially eliminated. It is, of course, to be understood that although other means for securing the bundle wrapper can be used, the deformed strap seal permits materially reduced space between the tube bundle and shell with a resulting increase in tube bundle size for any predetermined size of shell.

The sealing of the respective cover member, channel, and tube sheet members to the shell is

preferably accomplished by a frusto-conical form of gasket heretofore described in a copending application of the present inventor, filed November 3, 1937, Serial No. 172,567. These gaskets, indicated at 50, are provided between the cover 12 and the ring 51, which is secured to the shell 10; between the fixed tube sheet 14 and the shell 10; and between the channel member 21 and fixed tube sheet 14 and channel cover 23; and 10 between the floating tube sheet cover 18 and the skirt extension 56 on the floating tube sheet 16. Each of the respective members has complementary shoulders with relatively rounded corners in which the gasket forms a seal due to 15 the relative change of its angular relation, which change causes a tightening of the gasket on the edges. When the parts are moved to a closed position by a series of adjustable screws 52, which are preferably carried by a sectional bull ring 53, interlocked at 54 to a projection of the shell 10 or of the portion 11, or of the portion 56, the gasket turns to a sealing position.

This sealing movement may be in the range of from approximately 30° to 40° or less when unsealed to a sealed condition of approximately 20° to 10°. The relative angularity required can be determined by the amount of tolerance provided and it is based on the major diameter of the gasket itself, the total movement being the difference between the cosines of the angle. As the seal is provided between the respective shoulders against which the gasket cooperates, a secondary seal can be provided between the cover 18 and the channel member 17 and between the channel member 17 and the floating tube sheet 16 as by flat gaskets 57 and 58, such gaskets preventing any possible erosion of the metal.

It will be noted that the three frusto-conical gaskets 50 at the channel end are each held in position by a single series of adjustable screws 52, which is possible without excessive size screws as the sealing pressure of the gaskets is independent of the pressure that holds the cover, channel, and floating tube sheet to the shell. The toggle action of the gaskets gives a relatively high mechanical advantage, which increases as the gasket is moved to its sealed position.

The gaskets are preferably somewhat softer than the shoulders with which they cooperate so that there will be some flow of metal and all crevices will be filled. The gaskets, however, are preferably of a resilient metal so that they will continuously maintain a seal and, when the pressure is relieved, they will tend to return to their original shape.

Removal of the tube bundle 15, without breaking the external connections to the shell nozzles, is accomplished by retractable connections to the 60 channel and to the bundle wrapper. The bundle wrapper nozzle 33 is detachably secured to a ring member 35 of saddle form, which is welded substantially fluid-tight to the shell. The manner of attachment includes the studs 78 and a 65 form of frusto-conical gasket 80, heretofore described. The bundle wrapper 21 has an opening 27a in alignment with the shell nozzle 33, and a retractable coupling 70, which is carried by the saddle ring 35, is movable into contact 70 with the bundle wrapper 21 surrounding the opening 27a. The seal is maintained by the pressure screws 73, which force the gasket 75 into contact with the saddle ring 35 and the gasket 76 into contact with the bundle wrapper. The jackscrews 81 are alternated with the pres-

sure screws 73 so that the retractable coupling 70 may be withdrawn. Both the jackscrews 81 and the pressure screws 73 are provided with caps 82 and 83 to prevent leakage.

Retractable connections are also provided for the channel connections and they may be used to great advantage irrespective of the use of a bundle wrapper, although they are especially valuable therewith. As more particularly shown in Fig. 2, the channel 21 is wholly within the 10 shell and the shell is provided with fixed nozzles 22. This nozzle has a movable sleeve 158 which is provided with suitable shoulders for cooperative relation with gaskets 159 and 160. These gaskets engage shoulders on the fixed nozzle 22 and the channel 21 respectively.

Movement of the retractable sleeve 158 is accomplished by screws 162 in screw threaded engagement with the interior of the fixed nozzle 22 and in abutting relation with the sleeve 158 and being adapted to engage shoulders 158a to force the sleeve into sealed position and adapted to engage shoulders 158b to retract the sleeve. In the retracted position of the sleeve, the channel and tube bundle may be completely withdrawn from the shell. Retraction is accomplished from the exterior of the shell by the screws 162, which extend through the pipe flange 163, and no pipe connections need be broken for this purpose.

Removal of the tube bundle without destroying the external nozzle connections to the channel can also be accomplished by using either of the retractable forms of connection shown in Fig. 3 or 4. In Fig. 3 the shell 90 has the pipe nozzles 91 integrally secured thereto as by the flange 92, welded to the shell. The channel is indicated at 94 and is secured between the channel cover 95 and the fixed tube sheet 96 by the pressure screws generally indicated at 52 and the bull ring 53. As in the prior construction, the channel 94 is sealed with respect to the cover 95 and the fixed tube sheet 96 by a plurality of gaskets 50 of the frusto-conical type.

The nozzle 91 is sealed with respect to the channel 94 by a retractable sleeve or collar 98 which is held against the nozzle by the screws 99. The parts are sealed together by a plurality of gaskets which may also be of the frusto-conical type 97, certain of which are between the channel 94 and the collar 98 and certain of which are between the collar 98 and the nozzle 91. By the use of the frusto-conical gaskets, it is possible to simultaneously seal the retractable member with respect to the channel and nozzle inasmuch as the gaskets commence to seal as soon as they rotate, and the seal is increased in effectiveness as the parts are drawn together.

In Fig. 4 the shell 110 is provided with a detachable nozzle 111 held by the screws 112. As 60 in the prior form, the nozzle 111 is made pressure-tight with respect to the channel 114 by a form of frusto-conical gasket 113 which, in this case, engages a shoulder on the nozzle 111 and a shoulder on the channel 114. By tightening up on 65 the screws 112, the gasket will be rotated in toggle fashion to set up the desired seal. The channel 114 is secured to the fixed tube sheet 116 and cover 119 by the screws 52 and bull ring 53. The jackscrews 120 can be used to partially retract the nozzle 111 and, when retracted a sufficient distance, the channel will clear the end of the nozzle. A suitable retaining member in the form of a wire 121 is provided to assist in 70

positively withdrawing the gasket 113 to break the seal.

In each of these forms, external pipe connections need not be broken in order to remove the tube bundle as in Fig. 3. The connection is broken within the shell by a retractable member, and in Fig. 4, the small amount of retraction necessary for the pipe connection 111 can be accomplished by the jackscrews.

10 It will thus be apparent that the heat exchanger can be provided with a removable tube bundle which can be removed from the shell without breaking external pipe connections. This is irrespective of whether it be provided 15 with a bundle wrapper. In each case, the entire channel is effectively sealed within the shell but without any reduction of effective tube area as the floating tube sheet can be almost as large as the shell. All external flanges are eliminated 20 and by using the bundle wrapper a more effective confinement of the fluids about the tubes is accomplished.

This application is a division of my copending application Serial No. 174,330, filed November 25 13, 1937.

While I have shown preferred forms of embodiment of my invention, I am aware that other modifications may be made thereto and I, therefore, desire a broad interpretation of my invention within the scope and spirit of the description herein and of the claims appended hereinafter.

I claim:

1. In a heat exchanger, a shell, fluid nozzles secured thereto, a removable tube bundle assembly including a fixed tube sheet, a channel and a channel cover, means to connect the tube bundle to the fluid nozzles, said means including a retractable coupling between the nozzles and the channel.

2. In a heat exchanger, a shell, external pipe connections secured thereto, a removable tube bundle assembly including a fixed tube sheet, a channel and channel cover, means to connect the channel and external pipe connections including a retractable coupling between the pipe connections and the channel, and frusto-conical gasket means to seal the coupling with respect to the pipe connection.

3. In a heat exchanger, a shell, external pipe connections secured thereto, a removable tube bundle assembly including a fixed tube sheet, a channel and channel cover, means to connect the channel and external pipe connections including a retractable coupling between the pipe connections and the channel, and gasket means to seal the coupling with respect to the pipe connection, and means to retract the coupling to break the connection between the channel and nozzle, said 10 means including means operable from the exterior of the shell.

4. In a heat exchanger, a shell, a fixed pipe connection integral with the shell, a removable tube bundle assembly having a header channel 15 and means to interconnect the pipe connection and the header channel including a retractable coupling, said retractable coupling having sealing gaskets engaging the channel and other sealing gaskets engaging the fixed pipe coupling, and 20 means to draw down said retractable coupling on both of said gaskets to simultaneously seal the parts.

5. In a heat exchanger of the class described, 25 a shell, fluid nozzles permanently secured thereto, a tube bundle having a bundle wrapper within said shell, said bundle wrapper having an opening substantially in alignment with one of said nozzles, a channel for said tube bundle having an opening opposite another nozzle, and retractable means between said respective nozzles and openings whereby said openings may be interconnected and disconnected to said nozzles without destruction of external connections to said 30 nozzles.

6. In a heat exchanger of the class described, 40 a shell, a tube bundle assembly therein including a tube bundle, a channel and a channel cover, a wrapper for said tube bundle, fluid nozzles connected to said shell, connections between said nozzles and said bundle wrapper and said tube bundle assembly, respectively, said connections comprising internally retractable members whereby said tube bundle may be withdrawn from the shell without breaking external connections 45 to the nozzles.

GEORGE T. JACOCKS.
